(57) **CLAIM**

The ornamental design for TV receiver with pictorial image, as shown and described.

DESCRIPTION

FIG. 1 is a perspective view of the images of the ornamental design of the present invention as shown on a monitor screen;

FIG. 2 is a front elevational view of the ornamental design of the present invention shown in FIG. 1; and,

FIG. 3 is an enlarged view of the pictorial image of FIG. 2. The broken line showing of a monitor and monitor speakers is included for the purpose of illustrating environmental structure and forms no part of the claimed design.
